DISPENSER FOR PAPER SHEETS

Harold W. Berger, Omaha, Nebr.

Application March 30, 1938, Serial No. 199,002

1 Claim. (Cl. 312—58)

This invention relates to a dispenser for paper sheets and more particularly to a new device for dispensing paper towels, napkins, and the like.

One feature of my invention is that the sheets of paper or similar material are dispensed only in predetermined units; another feature is that the paper sheets are inaccessible to the user until the device is operated; still another feature is that overlapping sheets are avoided; other features and advantages will appear from the following specification and drawings, in which:

Figure 1 is a side elevational view of one embodiment of my invention; Fig. 2 is a view, partly broken away, along the line 2 of Fig. 1; Fig. 3 is a plan view with the cabinet cover removed; Fig. 4 is a fragmentary vertical sectional view with the end of a paper towel projecting from the dispenser; and Fig. 5 is a perspective view of a paper towel.

In dispensers of this type heretofore commonly used, the device normally permits a single towel to project from the cabinet, accessible to the user. The removal of this towel by an overlapping arrangement of the towels then draws the next towel into the accessible position. The disadvantage of a device of this type is that the user may waste the towels by pulling out two or three at one time. Other devices provide for the dispensing of a single or a predetermined number of towels at one time, but the mechanisms are so complicated that they are expensive and easily get out of order. The embodiment of my invention disclosed herein dispenses a single or a limited number of towels and is simple to operate and inexpensive to manufacture.

While my invention is described, for the purposes of illustration, in connection with the use of paper towels, it will be apparent that any material which can be suitably folded may be used as well. Other materials with which my invention has been found to be particularly useful are toilet paper and paper napkins.

In the particular embodiment of my invention described herein, a cabinet 10 serves as a container for the paper towels. The cover 11 for the cabinet is preferably sloping or curved, in order that articles will not be placed thereon, and may rise from each side at an angle of 30° or 40° to a peak, as shown.

Along the sides of the cabinet at the base thereof, two supports 12 and 13, with inwardly turned flanges 14 and 15, are secured thereto by rivets or screws 16. The ends of said supports project beyond the ends of the cabinet and serve as a base for the mounting of the dispensing mecha-

nism. Two rods 17 and 18 are fixedly mounted on the ends of said supports, preferably beyond the ends of the cabinet 10 or at least beyond the ends of the paper towels in order that they may not interfere therewith.

A flat plate 19 is slidably mounted on the rods 17 and 18, preferably by simply bending the ends of the plate around the rods. The width of the plate may be suitably adjusted to the type of towel or other paper sheet used but is usually approximately one-half the width of the cabinet. Small stops 20, fixed on the rods, limit movement of the plate towards one side of the cabinet 10 and a spring 21 urges the plate away from the other side of said cabinet, thus retaining the plate 19 in what will be called its normal position in approximately the center of the cabinet.

A handle 22 of any suitable type is attached to the plate 19 enabling the user to slide the plate 20 towards the side of the cabinet against the urging of the springs 21. The handle 22 is preferably centrally located on the plate to assist smooth, even slidability. It is also desirable to attach to the plate small projecting fingers 23 and 24 which aid in forcing exposed towels into a more accessible position.

The paper towels 25 must be suitably folded for use in my dispensing device. At least one end 26 of said towel should be folded backwardly 30 under the main body thereof in order that said end may rest on the plate 19 when the plate is in its normal position.

Because symmetrical sheets are simpler to manufacture and more easily properly placed in the cabinet, it is usually desirable that the other end 27 of the paper towel should also be folded under the main body of the sheet. At any rate, if the end 27 is so folded, the fold should be of a sufficient depth that the end 27 may also rest on the plate 19 when the plate is in its normal position.

Thus, as shown particularly in Fig. 5, the ends 26 and 27 of the towel 25 may be folded backwardly under the main body thereof. The ends 45 are preferably adjacent to each other but not overlapping. The space between the two ends should be less than the width of the plate 19.

The folded paper towels are made in a suitable size to enable them to fit snugly in the cabinet 50 10. The flanges 14 and 15 serve as the primary support for the sheets when in place in the cabinet. In addition, the ends 26 and 27 rest upon the plate 19.

The operation of my invention is extremely 55

simple. By means of the handle 22, the plate 19 is pulled to the side of the cabinet 10. In this position the plate 19 no longer supports the end 26 of the paper towel 25 and said end immediately drops down below the level of the plate. When the handle 22 is released, the spring 21 urges the plate 19 back to its normal position and the fingers 23 and 24 force the end of the paper down into a more accessible position. The user 10 then grasps the end of the paper towel and removes it by pulling it out. If another sheet is desired, the operation is repeated.

It is obvious that various means other than the handle 22 may be used to operate the device. 15 For instance, by means of the usual spring and lever arrangement (not shown) it may be operated by pressing a button. Or one of the usual types of coin control devices (not shown) may be connected therewith making the device oper- 20 able only upon the insertion of a coin.

Ordinarily, it will be desirable to dispense only a single sheet with each operation. However, towels may be dispensed in groups of two or any other predetermined unit by interfolding them in 25 such groups.

The foregoing detailed description has been given for clearness of understanding only, and no unnecessary limitations should be understood therefrom, but the appended claim should be 30 construed as broadly as permissible, in view of the prior art.

I claim:

In a dispenser for paper towels adapted to permit only one towel to be removed therefrom by a single operation by the user thereof, a cabinet adapted to receive a plurality of towels, each of 5 said towels having at least one end thereof folded backwardly under the main body of said towel, said cabinet having an opening in the bottom thereof through which said towels may be removed, members in said cabinet on opposite sides 10 of said opening for supporting said towels in vertically stacked relation in said cabinet with the folded end of each towel extending from one side of the cabinet under a portion of the main body of the towel, a horizontal plate carried by said 15 cabinet covering a portion of said opening, said plate when in normal position being adapted to support the folded end of the lowermost of said towels in a position inaccessible to the user thereof, said plate being horizontally slidable across 20 said opening towards the other side of said cabinet to a position out of contact with said folded end of said towel, permitting said end to become accessible to the user thereof through said opening, and spring means for urging said plate to 25 normal position, leaving a single towel in a position of access to the user.

HAROLD W. BERGER.
